PAGE 2

Fig. 2

Fig. 5

Fig. 1 is a front perspective view of a swing-shelf display rack or the like, showing my new design, with the shelves in lowered position.

Fig. 2 is a view similar to Fig. 1 showing the shelves in fully raised position.

Fig. 3 is an elevational view of the side of the device opposite the side illustrated in Fig. 1 with the shelves in lowered position.

Fig. 4 is an elevational view of the side of the device opposite the side illustrated in Fig. 2 with the shelves in raised position.

Fig. 5 is a rear elevational view of the device of Fig. 1. I claim:

The ornamental design for a swing-shelf display rack or the like, as shown.
